UNITED STATES PATENT OFFICE

KENNETH C. GARNER, OF HAMLET, NORTH CAROLINA

PANTS RACK

Application filed March 1, 1932. Serial No. 596,123.

This invention relates to a rack designed particularly for holding and displaying pants and like garments and the present invention is an improvement over the rack forming the subject matter of my copending application Serial No. 537,720 and filed under date of May 15, 1931.

In accordance with the present invention, a rack is provided characterized by having an upper arm, together with a rod cooperating with the upper arm for clamping a garment or the like therebetween together with improved means for securing the garment against casual displacement when so clamped on the rack, and also means for effecting a positive engagement of the rod with the arm whereby to prevent casual displacement of the rod, the last named means being characterized by facility of operation.

The present invention together with its many objects and advantages will be best understood from a study of the following description, taken in connection with the accompanying drawing, wherein:

Figure 1 is a side elevational view of the improved rack, the same being mounted on a suitable support, and with the rod and rack arm in cooperative clamping relation.

Figure 2 is an enlarged sectional elevational view taken substantially on the line 2-2 of Figure 1.

Figure 3 is a perspective view of the clamping rod.

With reference to the drawing it will be seen that the rack is preferably formed of wire or other suitable material, and includes a bracket having angularly disposed arms including a substantially horizontal arm 5 and an inclined arm 6 connected at its upper end with the arm 5. The free ends of the arms 5 and 6 are provided with depending pintles 7 adapted to be journaled in recesses provided in parallel bars 8 forming part of a suitable support. As suggested in the drawing, such support may consist of one or more pairs of such bars 8 supported between a pair of uprights, a portion of one of which is shown in the drawing and designated by the reference numeral 9.

Arm 5 adjacent the end thereof provided

with the pintle 7 is provided with an eye 13, and adjacent that end connected with the arm 6, is provided with a substantially elongated keeper eye 10.

The improved rod is designated by the numeral 11, and the same at one end is provided with an eye 12 loosely engaging the eye 13. At its free end the rod 11 is provided with a return bend 14 that merges into a depending extension 15 having a return bend 16, the parts 15 and 16 forming a substantially U-shaped handle, and the parts 16 adjacent its upper portion being again bent into a U 17, opposed portions of which adjacent the open side of said U are bent over the rod 11 to extend laterally therefrom in substantially a horizontal plane.

The U-shaped part 17 forms a latch member, and one leg of the U 17 adjacent the open end of the U is turned downwardly and then upwardly about the return bend 14 and the proximate portion of the rod 11 and is then continued upwardly to provide a shank 18 which will be found to provide a support or attaching means for a card (not shown) on which may be suitable advertising or other indicia.

One side of the U 17 is crimped or bent inwardly as at 17a for positive engagement with a proximate side of the keeper eye 10 when the latch part 17 is passed through the eye for locking the bar 17 in clamping relation with respect to the arm 5.

The rod 11 intermediate its end has a portion thereof bent into a substantial V providing a depending extension 19 for engagement with the garment folded over or draped about the arm 5.

In actual practice, it will be seen that the pants or like garment may be folded over the arm 5 of the bracket which is swingably mounted on the support in a manner hereinbefore stated. The retaining rod 11 is then swung to a position substantially parallel with the arm 5, whereby the trouser will be clamped between said arm 5 and the rod. The rod 11 is retained in its clamping position, by passage of the keeper 17 through the eye 10, and subsequent engagement of the part 17a of the keeper with a proximate

100

side of the eye 10. In this connection, it will be noted that the keeper 17 being U-shaped and the entire structure being formed of wire, will be resilient, so that initial insertion of the parts 17 through the eye 10 will cause a contraction of the part 17 and subsequent expansion thereof so that a portion of the eye 10 will be received in the bend 17a whereby the keeper and latch member 17 will be positively engaged one with the other.

With the rod 11 so secured in clamping position, the projection or part 19 thereof will have bearing engagement with the garment so that the latter will be retained against casual displacement. The projection 19 will be found especially useful in the event a garment other than trousers be arranged over the arm 5, and especially if such garment be of the flimsy type such as a dress or the like.

To release the latch 17, parts 15 and 16 are grasped in the hand, and part 15 flexed toward the part 16 whereupon the curved portion of the U-shaped part 17 is moved out of engagement with the eye 10 and the part 17 then readily withdrawn through the eye 10.

Even though I have herein shown and described the preferred embodiment of the invention it is to be understood that I do not wish to limit myself to the precise details of construction, combination and arrangement of elements herein shown but claim all such parts of the invention to which I am entitled in view of the requirements of the prior art and the scope of the appended claims.

Having thus described my invention, what I claim as new is:

1. A bracket of the class described comprising in combination an arm, a rod loosely connected with the arm at a corresponding end of the arm, said arm remote from said end being provided with an eye, and said rod having a substantially U-shaped part extending laterally therefrom and adapted to be passed through said eye and engaged therewith for retaining said rod in clamping relation with respect to said arm.

2. A bracket of the class described comprising in combination an arm provided adjacent one end with an eye, a rod loosely engaged at one end with a corresponding end of said arm, said rod being provided adjacent its free end with a return bend merging into a depending U, which in turn merges into a second U extending at right angles to the first named U and arranged for passage through said eye and engageable with said eye for securing said rod and arm in clamping relation.

3. A bracket of the class described comprising in combination an arm, a rod loosely connected with said arm at one end, said arm at its free end being provided with an eye, and said rod at its free end provided with a return bend merging into a substan-

tially vertical U which in turn merges into a second U extending laterally of said rod and engageable with said eye, said second U having one side thereof provided with a free portion wrapped about said return bend and a corresponding portion of said rod and extending upwardly to provide a card supporting shank.

4. A bracket of the class described comprising in combination an arm, a rod loosely connected at one end thereof with one end of said arm, said arm remote from said one end being provided with an eye, and said rod having a substantially U-shaped part extending laterally therefrom and adapted to be passed through said eye and engage therewith to retain said rod in clamping relation with respect to said arm, said rod intermediate its ends having a portion thereof extending downwardly from the plane of said rod for engagement with an article of apparel or the like clamped between said rod and arm.

In testimony whereof I affix my signature.

KENNETH C. GARNER.
